Belknap Attorney

UNITED STATES PATENT OFFICE.

DEAN M. SOLENBERGER, OF KANSAS CITY, MISSOURI.

PISTON RING.

Original application filed April 9, 1924, Serial No. 705,172. Divided and this application filed January 25, 1926. Serial No. 83,715.

To all whom it may concern:

Be it known that I, DEAN M. SOLENBERGER, a citizen of the United States of America, residing at Kansas City, in the 5 county of Jackson and State of Missouri, have invented certain new and useful Improvements in Piston Rings, of which the following is a specification, reference being had therein to the accompanying drawings.

The invention relates to piston rings of that type provided with staggered circumferential series of overlapping slots which render the ring axially, resiliently compressible. The present invention is a divisional 15 of a pending application Serial No. 705,172 filed April 9, 1924, and the invention consists in the construction as hereinafter set forth.

20 In the drawings;

Figure 1 is a side elevation of the ring, constructed in accordance with my invention.

Figure 2 is a fragmentary vertical sectional view through a piston and cylinder showing my improved ring in engagement therewith.

Describing the various parts by reference characters 1 denotes a cylinder and 2 a piston reciprocable therein and provided with one or more circumferential grooves 3 for the reception of the sealing rings. One or more of these rings are constructed in accordance with my invention and preferably 30 similar to that shown particularly in Figure 1, wherein 4 denotes the sealing ring which is provided with a plurality of upper and lower spaced overlapping circumferential slots 5. These slots are preferably so arranged that they define outer bars 6 and central bars 7, said outer bars being connected at spaced intervals by solid portions 8 to the central bars. This arrangement permits the ring to be compressed longitudinally 40 at all points so that when inserted in a ring groove, the ring will automatically exert a slight pressure against the side edges of the ring groove and accommodate itself evenly to ring grooves which are worn or of slightly varying widths. It will be noted that outer bars are of greater width

than the centre bars. By varying the length, breadth and thickness of the centre bars I am enabled to control the longitudinal pressure exerted by the ring against the 55 side edges of the ring groove. A relatively thin centre bar as shown permits me to obtain a relatively low longitudinal pressure as will be explained more fully hereinafter. Also it will be noted that by providing 60 relatively wide outer bars, the danger of breakage due to handling of the ring when installing the same, is reduced to a minimum.

The stepped joint indicated at 10 is preferably so arranged that the circumferential line of overlap of the tongue is to one side of the circumferential axis of the ring so as to provide strong and durable tongues 11. The joint as a whole is rendered flexible 70 by continuing one of the slots 5 across the joint.

A ring constructed as described when placed in a ring groove 3 somewhat less in width will exert a predetermined axial pressure due to the flexing and resiliency of the comparatively thin central bars 7. This will maintain sealing contact between the ring and the side walls of the groove.

What I claim as my invention is:

1. A one piece ring having an upper and a lower circumferential series of slots, the said ring being provided with a stepped split joint comprising upper and lower overlapping tongues, the slots in one series being staggered with respect to those in the other series, one of the lower slots extending circumferentially across the lower tongue to divide said tongue into two portions, and the line of overlap of said 90 tongues being disposed to one side of the circumferential axis of the ring.

2. A one piece piston ring having an upper and a lower circumferential series of slots the slots in one series being staggered with respect to those in the other series to define a series of upper, lower and intermediate bars, said intermediate bars having a width substantially less than said upper and lower bars.

In testimony whereof I affix my signature.
DEAN M. SOLENBERGER.
